FIG. 4

FIG. 5

FIG. 6

FIG. 7

FIG. 8

FIG. 9

FIG. 10

FIG. 11

FIG. 12

FIG. 13

FIG. 1 is a front, top and left side perspective view of a portable microfiche viewer, with cover raised, showing my new design;

FIG. 2 is a front elevational view thereof;

FIG. 3 is a front, top and right side perspective view thereof;

FIG. 4 is a rear elevational view thereof;

FIG. 5 is a bottom plan view thereof;

FIG. 6 is a right side elevational view thereof;

FIG. 7 is a left side elevational view thereof;

FIG. 8 is a front, top and left side perspective view thereof, but with the cover closed;

FIG. 9 is a front elevational view thereof;

FIG. 10 is a front, top and right side perspective view thereof;

FIG. 11 is a rear elevational view thereof;

FIG. 12 is a bottom plan view thereof; and

FIG. 13 is a right side elevational view thereof. Thus, FIGS. 8 through 13 are views like those in FIGS. 1 through 6, respectively, but with the cover closed and to somewhat different scale.

I claim:

The ornamental design for a portable microfiche viewer, as shown and described.
